(57) **CLAIM**

We claim the ornamental design for a footwear care machine, as shown and described.

DESCRIPTION

FIG. 1 is a front perspective view of a footwear care machine showing a new design;

FIG. 2 is a bottom perspective view thereof;

FIG. 3 is a front view thereof;

FIG. 4 is a rear view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a partial enlarged detail view of the portion designated 9 in FIG. 1;

FIG. 10 is a cross-sectional view taken along the line 10-10 in FIG. 9;

FIG. 11 is a perspective view of the claimed portion of the footwear care machine shown separately from the main body; and,

FIG. 12 is a front right perspective view of the footwear care machine showing in a state of use.

The broken lines represent portions of the footwear care machine that form no part of the claimed design. The broken lines shown in FIG. 12 are for the purpose of illustrating environmental structures and form no part of the claimed design. The dot-dot-dash broken lines shown in FIGS. 1, 9

(Continued)

and **10** indicate cutoff boundaries for the enlarged detailed portion views and form no part of the claimed design.
